CLAIM

The ornamental design for a charger for head mounted display device, as shown and described.

DESCRIPTION

FIG. 1 is a perspective view of a charger for head mounted display device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof where the bottom plan view is a mirror image; and,

FIG. 7 is a perspective view thereof, showing an example of the usage of the subject design.

The broken lines show unclaimed subject matter only and form no part of the claimed design.
